[57] CLAIM

The ornamental design for a tape measure, as shown and described.

DESCRIPTION

FIG. 1 is a top, front, and right side perspective view of a tape measure showing my new design;

FIG. 2 is a top, front, and right side perspective view, with the tape extended and the foot in transverse position;

FIG. 3 is a right side elevational view, the left side elevational view being a mirror image;

FIG. 4 is a top plan view;

FIG. 5 is a bottom plan view;

FIG. 6 is a rear elevational view; and

FIG. 7 is a front elevational view thereof.
